(57) **CLAIM**

The ornamental design for a photovoltaic charger, as shown and described.

DESCRIPTION

1. Photovoltaic charger

Figure 1.1. is a right side view;

Figure 1.2 is a left side view;

Figure 1.3 is a rear view;

Figure 1.4 is a perspective view;

Figure 1.5 is a front view;

Figure 1.6 is a bottom view; and

Figure 1.7 is a top view.

In the reproductions, the broken lines are for the purpose of illustrating portions of the photovoltaic charger that form no part of the claimed design.
